UNITED STATES PATENT OFFICE

157,892

MOVIE PROJECTOR

Harris E. Nelson, Frank Lustig, and Burt E. Schell, Chicago, Ill., assignors to Revere Camera Company, Chicago, Ill., a corporation of Delaware

Application September 18, 1948, Serial No. 148,646

Term of patent 14 years

(Cl. D61—1)

To all whom it may concern:

Be it known that we, Harris E. Nelson, Frank Lustig, and Burt E. Schell, citizens of the United States, residing at Chicago, in the county of Cook and State of Illinois, have invented a new, original, and ornamental Design for a Movie Projector, of which the following is a specification, reference being had to the accompanying drawings, forming a part thereof, in which,

Fig. 1 is a side elevational view of a movie projector showing our new design;

Fig. 2 is a top view thereof;

Fig. 3 is a front elevational view thereof;

Fig. 4 is a side elevational view of the opposite side to that shown in Fig. 1, and

Fig. 5 is a rear elevational view thereof.

We claim:

The ornamental design for a movie projector, as shown.

HARRIS E. NELSON.
FRANK LUSTIG.
BURT E. SCHELL.
